United States Patent Office.

JAMES COYLE, OF BOSTON, MASSACHUSETTS.

Letters Patent No. 88,014, dated March 23, 1869.

IMPROVED FLOUR-SIFTER.

The Schedule referred to in these Letters Patent and making part of the same.

To all whom it may concern:

Be it known that I, JAMES COYLE, of Boston, in the county of Suffolk, and State of Massachusetts, have invented a new and improved Flour-Sifter; and I do hereby declare that the following is a full, clear, and exact description thereof, which will enable others skilled in the art to make and use the same, reference being had to the accompanying drawings, forming part of this specification.

This invention relates to improvements in flour-sifting apparatus, such as used for sifting and pulverizing the flour previous to cooking.

It consists of a rectangular screen, arranged to slide to and fro on a frame, and provided with a set of crushing-rollers, suspended from the bed-frame within the said sieve, in contact with the bottom, so as to be rotated by the said bottom as the sieve is reciprocated, as will be hereinafter specified.

Figure 1 represents a longitudinal sectional elevation of my improved apparatus, and

Figure 2 represents a plan view of the same.

Similar letters of reference indicate corresponding parts.

A represents a rectangular frame, provided with friction-rollers, and

C represents a rectangular sieve, arranged to be reciprocated thereon by hand.

D represents another rectangular frame, suspended, within the sieve, from the sides of the frame A, and provided with any suitable number of rollers, which are supported thereby above the bottom of the sieve, transversely and in contact therewith.

The flour is placed in the sieve, and the latter reciprocated, giving it a shaking-motion, and communicating rotary motion to the rollers, whereby any lumps will be crushed between the said rollers and the bottom of the sieve.

Having thus described my invention,

I claim as new, and desire to secure by Letters Patent—

The rectangular frame A, sieve C, and rollers E, suspended therein, when combined substantially as specified.
